US0D1035283S

(12) **United States Design Patent** (10) **Patent No.:** **US D1,035,283 S**
(45) **Date of Patent:** **** Jul. 16, 2024**

(54) **CONNECTOR**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Alexandre B. Girard**, Sunnyvale, CA (US); **Jonathan Gomez Garcia**, San Francisco, CA (US); **M. Evans Hankey**, San Francisco, CA (US); **Anne-Marie Heck**, San Francisco, CA (US); **Moises Hernandez Hernandez**, Palo Alto, CA (US); **Richard P. Howarth**, San Francisco, CA (US); **Julian Jaede**, San Francisco, CA (US); **Duncan Robert Kerr**, San Francisco, CA (US); **Kainoa Kwon-Perez**, San Francisco, CA (US); **Nicolas Pedro Lylyk**, Los Gatos, CA (US); **Peter Russell-Clarke**, San Francisco, CA (US); **Benjamin Andrew Shaffer**, San Jose, CA (US); **Clement Tissandier**, San Francisco, CA (US); **Eugene Antony Whang**, San Francisco, CA (US)

(73) Assignee: **Apple Inc.**, Cupertino, CA (US)

(**) Term: **15 Years**

(21) Appl. No.: **29/815,825**

(22) Filed: **Nov. 17, 2021**

(51) LOC (14) Cl. **03-01**

(52) **U.S. Cl.**

USPC **D3/318**; D13/108

(57) **CLAIM**

The ornamental design for a connector, as shown and described.

DESCRIPTION

FIG. 1 is a front perspective view of a connector showing the claimed design in an environment in which it may be used; FIG. 2 is a rear perspective view thereof;

FIG. 3 is a front view thereof;

FIG. 4 is a rear view thereof;

FIG. 5 is a left side view thereof;

(Continued)

FIG. 6 is a right side view thereof;
 FIG. 7 is a top view thereof; and,
 FIG. 8 is a bottom view thereof.
 The broken lines in the figures show environment and form
 no part of the claimed design.

1 Claim, 6 Drawing Sheets
